CARLO PIZZORNO, OF GENOA, ITALY

POWER LOOM IN ORDER TO OBTAIN BROCADES THEREFROM

Application filed August 18, 1924, Serial No. 731,839, and in Italy August 20, 1923.

The invention relates to brocading devices for mechanical weaving looms provided with a jacquard mechanism. According to the invention, the brocade batten comprises a stationary bar and a vertically and horizontally movable bar on which are arranged several groups of bobbins with different colored threads in rotatable bobbin holders, the bobbins of different color of one group of bobbins working with the same warp threads. The new device has the advantage that embroidery patterns having two and more different colors can be produced in a simple manner. The device is particularly adapted for such patterns, wherein the same design is repeated in different colors. By shifting the movable bar in a horizontal direction from the jacquard machine, the bobbin having the desired color is selected and placed over those warp threads where the embroidery pattern is to be provided. By shifting the movable bar vertically and turning the bobbin holders, the brocade thread is then put on the warp threads.

The invention is illustrated in the accompanying drawing by way of example.

Fig. 1 is a front elevation of a weaving loom provided with a jacquard machine, whereon the new brocade device is applied;

Fig. 2 is the front elevation of the driving gear for the bobbin holder on an enlarged scale;

Fig. 3 is a side elevation of this driving gear;

Fig. 4 is the front elevation of the movable and the stationary part of the brocade batten;

Fig. 5 is a front elevation of the bobbin with its holder;

Fig. 5^a is a fragmentary longitudinal section through the bobbin and the bearing therefor showing in detail the mounting of the bobbin spindle.

Fig. 6 is a plan thereof;

Fig. 7 is the front elevation of the slotted member belonging to the driving gear according to Fig. 2.

The bobbins, which receive the brocade threads, are designated 256 and 261 (Figs. 1 and 4). The bobbins are operated by a pul-

ley, shown in Figs. 2 and 3 and comprising two side discs 200 and 201 and a central disc 202. These discs are rotatable on a pivot 203 mounted in a holder or support 204. A friction disc 227, which is fixed to the holder or support 204 and can be pressed against the disc 200 by means of the nut 228 and the washer 229, enables a regulation of the pulley rotation.

The disc 200 is provided with diametrically opposed recesses or grooves 223, 224; furthermore, the same disc has recesses or grooves 225 and 226, which are also diametrically opposed.

The central disc 202 has two grooves or recesses 214 and 215, in which a pin 213 fits, which is carried or supported by two parallel chains 208. These chains engage the central disc 202. One end of the chain is fastened to a spring 209 by means of the hook 210 where- 65 as at the other end of the chain a hook 212 is provided for a rope 211.

The side disc 201 has a crank arm 205 and a crank pin 206, the latter coaxing with a rod 207, which transmits during the rotation of the pulley a reciprocatory movement to the rack for moving or operating the brocade shuttle.

On the holder 204, a support 219 is provided wherein a pivot 218 is mounted. This pivot carries a pawl 216 whose tooth 221 can engage in the recesses or grooves 223, 224 of the disc 200. A spring 220 wound on the pin 218 tends to turn the pawl 216 so that the tooth 221 is lifted out of the recesses of the disc 200 (Fig. 2). A spring 217 connects one end of the pawl to the double chain 208. 80

A further pawl 222 is rotatable on the pivot 218. It engages under the action of its own weight in the grooves 225, 226 of the disc 200. 90

When the parts are in the position shown in Fig. 2 and the rope 211 is tensioned, the pin 213 engaging in the recess 214 produces 95 a semi-revolution of the pulley. By means of the spring 217 the chain simultaneously actuates the pawl 216 against the pressure of the spring 220 so that the tooth 221 engages in the groove 224 of the disc 200. This tooth 100

prevents a further rotation of the disc beyond 180°.

During this semi-revolution of the pulley, the crank 205 and the rod 207 are moved from right to left (Fig. 2).

As soon as the tension of the rope 211 slackens, the chain is returned under the action of the springs 209 to its original position, the tooth 221 being lifted out of the groove 224 by the spring 220. The pulley must however maintain its position, because the pawl 222, which in consequence of its own weight always bears on the periphery of the disc 200, engages in the groove 226 of this disc.

During the next pull of the rope 211, the pin 213 of the double chain 208 engages in the recess 215 of the central disc 202 and again turns the pulley through an angle of 180°. The stroke is again limited by the tooth 221, whereas during the return of the rope 211, the pulley is held in the new position by the pawl 222.

The rope 211 adapted to move the double chain 208 is secured at its upper end to the member 230, which is provided with slots 231, through which pins 232 extend, which allow of an upward and downward movement of the slotted member 230 and simultaneously limit its stroke. The pins 232 are secured to a plate, which is carried by a support 77 of the brocade loom. A hook 234 is adapted to swing at 233 on the upper end of the slotted member 230. The hook carries a balance weight 235 and is adjusted by a rope 236 of the jacquard device. If this hook is only under the influence of the balance weight 235, it will be turned from the position (shown in Fig. 1) counter-clockwise so that it comes out of the range of a lever 73 which is operated from the lower shaft of the loom by means of a rope. If, however, the rope 236 is tensioned, the hook will be swung clockwise, so that it comes into the path of the lever 73, as is shown in Figs. 1 and 7. As soon as the lever 73 ascends, the slotted member 230 and also the rope 211 are raised.

The whole of the movable and the stationary part of the brocade batten comprises a movable bar 237, having the bearings 238 provided with pivots 239, a holder or support 240 secured to one end of the batten, a lug or projection 241 on which one end of a spring 242 engages, which connects the bar 237 to the stationary part 243 of the batten by means of a projection 244 on which the other end of the spring 242 engages.

On the balls 245 arranged between the bar 237 and the stationary part 243 of the batten, the bar 237 can be shifted horizontally with respect to the stationary part 243 of the batten, said bar being guided by projections 246 of the batten.

The spring 96, which is secured to the trans-

verse bar 97 of the jacquard machine, carries two ropes 247, to which a shuttle bar 248 is suspended, which is movable both vertically and horizontally. The bar is connected to bar 237 by means of the forked supports 249, which receive between their forked ends the pivots 239 of the bearings 238. The bar 248 carries on three cylindrical pins 250 the rack 251, which has three longitudinal slots 252 wherein the pins 250 engage.

The rack 251 is moved horizontally by the rod 207 of the above-described driving gear and engages successively the cylindrical projections 253 of the shuttles 254 each of which carries the bearing 255 of its bobbin 256.

The bobbin 256 lies parallel to the plane of the carrier 254 (Fig. 5).

The bobbin 256 includes a spindle 260 one end of which is axially movable into rotatable position in one end of the bearing 255 being preferably tapered as shown in Fig. 5a to center the spindle in position. The opposite terminal of the spindle is axially movable and rotatable in an opening 255a formed in the opposite end of the bearing 255, the opening 255a being normally closed by a sliding ring or collar 258 movable upon the last mentioned end of the bearing 255. A spring 259 is interposed between the end of the bearing 255 and the bobbin 256 and normally retains the tapered end 260a of the spindle in proper bearing relation with the adjacent end of the bearing 255, while a second spring 257 secured to the bearing 255 normally retains the ring 258 in such position that its extremity 258a normally closes the opening 255a and prevents such axial displacement of the spindle 260 as will cause disengagement of its tapered extremity from the bearing. However, when it is desired to remove the bobbin the ring 258 is moved outwardly against the tension of the spring 257 thereby uncovering the opening 255 and permitting the spindle 260 to be moved axially against the tension of the spring 259, thus disengaging the tapered extremity 260a from the bearing and upon subsequent axial movement of the spindle in the opposite direction causing withdrawal of the spindle from the opening 255a and the removal of the bobbin.

By means of this brocade device, patterns having two and more different colors can be produced on mechanical looms with a jacquard machine. For this purpose, the bobbins of two shuttles, constituting one of a plurality of groups, are provided, for example, one 256 with a red thread and the other 261 with a green thread. Thus the brocading is done on the same warp threads, first with the red bobbin and then after displacement of the shuttle bar with the green bobbin.

If by means of the rope 262 coming from the jacquard machine and connected to the bar 237, the green bobbin has been brought

over the warp threads stipulated by the pattern, the green part of the embroidery pattern will be woven. The bobbin 261 winds the green thread around the warp threads, which are lifted by the jacquard machine.

5 If the rope 263 is then tensioned, which is connected on the one hand to the jacquard machine and on the other hand to the pawl 264 linked at 265 to the stationary part 243

10 of the batten, the pawl 264 will release the bar 237 as soon as it is removed from the adjustable tooth 266 so that the bar 237 may be shifted to the right under the tension of the spring 242. In this second position of

15 the bar 237, the bobbin 256 with the red thread passes over the raised warp threads, winds its thread around these warp threads and completes the pattern. When the one bobbin comes into action the other runs idle.

20 Having now particularly described and ascertained the nature of my said invention, and in what manner the same is to be performed, I declare that what I claim is:

1. In a mechanical brocade weaving loom, 25 groups of rotatable horse-shoe shaped brocade shuttles provided with thread spools, the shuttles of each group having different colored threads, the latter being adapted to be lowered alternately under the raised chain 30 threads in dependency of a jacquard machine, according to the two color brocade pattern to be produced on the base and connected with the latter by the base weft threads, a drive consisting of a wheel provided with 35 lateral discs and a central disc, a crank carried by one disc, a rod driven by said crank and connected with the brocade batten, a double chain arranged about one of the discs for driving the latter, a spring engaging with 40 the upper cross bar of the loom and connected with one end of the chain, and a cable attached to the other end of the chain.

2. A loom as claimed in claim 1 characterized by the provision of a pin on the chain, 45 teeth on the last mentioned disc engaged by the pin, a lever having a tooth at one end and a pawl-like tooth at the other end actuated by a spring arranged between it and the chain.

3. A loom as claimed in claim 1 characterized by the provision of a plate mounted on 50 the upper part of the loom connected with the said cable and having longitudinal slots therein, pins engaging said slots, a hook carried by the plate, a counter weight on said 55 hook, said hook being pivotally secured to the plate and rotatable under the action of the said cable.

4. A loom as claimed in claim 1 characterized by the provision of a brocade batten consisting of a movable rail, and a stationary rail, a spring connecting the two rails, a bar 60 movable horizontally and vertically which has a horizontal slidable rack, said shuttles engaging said rack and each including a spool 65 parallel to the shuttle bar, a ring, a spring

pressing the ring against the spool so as to prevent the latter from moving out of its support, and a spring holding the spindle of the spool.
